US00D878694S

(12) **United States Design Patent** (10) **Patent No.:** **US D878,694 S**
(45) **Date of Patent:** **** Mar. 17, 2020**

(54) **SCOURING ARTICLE**

- (71) Applicant: **3M INNOVATIVE PROPERTIES COMPANY**, St. Paul, MN (US)
- (72) Inventors: **Lauren K. Carlson**, St. Paul, MN (US); **Robert J. Maki**, Hudson, WI (US); **Amber D Rhy**, River Falls, WI (US); **Pamela L. Werley**, Minnetonka, MN (US)
- (73) Assignee: **3M INNOVATIVE PROPERTIES COMPANY**, Saint Paul, MN (US)
- (**) Term: **15 Years**
- (21) Appl. No.: **29/607,866**
- (22) Filed: **Jun. 16, 2017**
- (51) LOC (12) Cl. **07-05**
- (52) U.S. Cl. **USPC D32/40**
- (58) **Field of Classification Search**

(57) **CLAIM**

The ornamental design for a scouring article, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a scouring article showing the new design in a color photograph.

FIG. 2 is a top view thereof.

FIG. 3 is a bottom view thereof.

FIG. 4 a front view thereof, the back view being a mirror image of the front view shown; and,

FIG. 5 is a left side view thereof, the right side view being a mirror image of the left side view shown.

1 Claim, 1 Drawing Sheet
(1 of 1 Drawing Sheet(s) Filed in Color)
